COMBINED VENTILATOR AND LIGHT

William A. Norris, Alhambra, Calif.

Application August 23, 1943, Serial No. 499,648

9 Claims. (Cl. 230—259)

This invention relates to a combined ventilator and light.

The general object of the invention is to provide a novel combined ventilator and light particularly adapted for use in dwellings and wherein a single fixture includes a ventilating apparatus and a light so that a room may be both ventilated and lighted by means of a single fixture.

A more specific object of my invention is to provide an improved motor driven ventilator.

Another object of my invention is to provide an improved support for a motor driven ventilator.

Another object of the invention is to provide a novel air impeller for a ventilating device.

Another object of the invention is to provide a ventilator including a housing having a port therein with the closure for the port and wherein novel means is provided for operating the closure.

A further object of the invention is to provide a novel ventilator including a housing having a motor driven air impeller therein and wherein the housing is provided with a closure member which is moved to open position by operation of the motor.

Other objects and the advantages of my invention will be apparent from the accompanying description taken in connection with the accompanying drawings, wherein:

Fig. 1 is a central sectional view with parts in elevation showing my invention;

Fig. 2 is a sectional view on a reduced scale taken on line 2—2, Figure 1;

Figs. 3 and 4 are views similar to Fig. 2 taken on lines 3—3 and 4—4, respectively, Fig. 1; and

Fig. 5 is a central sectional view with parts in elevation showing a modification.

Referring to the drawings by reference characters, I have shown my invention as embodied in a combined light and ventilator which is indicated generally at 10. As shown the device includes a cylindrical housing 11 having a bottom closure 12 which may be welded thereto as at 13. The housing has a flange 13a thereon which fits in a hole 13b in a ceiling 13c and is held in place by screw 13d.

The closure 12 is provided with a plurality of apertures 14 through which air may pass into the housing. Arranged within the apertures 14 the closure 12 includes a depressed portion 15 forming a recess 16. In this recess 16 I arrange a boss 17 on the stator 18 of an electric motor. The top of the motor stator includes a boss 19 which is arranged in a recess 20 in a partition

member 21 which has an external flange 22 secured to the housing by bolts 23.

The closure 12 is of resilient material and is so arranged that it tends normally to flex upwardly as shown in dotted lines in Fig. 1. When moved downwardly (as shown in solid lines in Fig. 1) by engagement with the motor it serves to clamp the motor in place.

Arranged upon the closure 12 I show a valve member 24 which has a central aperture 25 which receives the hub 17. The valve member 24 includes apertures 26 which in one position of the valve member are aligned with the apertures 14 in the closure 12 and in another position are disposed between the apertures 14 so that passages for air are provided.

The closure 12 includes a pin 27 (see Fig. 1) which is upwardly directed and is arranged in an arcuate notch 28 in the valve 24. A spring 29 has one end attached at 30 to the valve 24 and at the other end to a post 31 on the wall of the housing 11. The spring normally tends to urge the closure 24 to closed position.

The motor stator 18 has a depending pin 32 thereon which fits in a recess 33 on a socket member 34 arranged in the closure 24. The construction is such that when the motor-stator 18 is rotated it will cause the valve 24 to rotate with the housing thus moving the valve against the tension of the spring 29 and aligning the ports 14 and 26. This occurs when the motor has started. When the motor ceases operation the spring 29 will rotate the member 24 and the motor to close the ports.

The motor includes an armature shaft or rotor 40 on which a housing 41 is secured by means of a screw 42. The housing 41 includes a flange 43 which engages a disc 44. The disc 44 has a central aperture 45 through which the armature shaft 40 extends.

Arranged upon the disc 44 I show a depending skirt 46 which has a plurality of spaced vanes 47 struck therefrom and bent inwardly. The vanes 47 are inclined in one direction and serve as impellers so that air is forced outwardly by the vanes 47. The skirt 46 has an outwardly extending flange 48 secured to the bottom thereof. This flange 48 is arranged close to the partition 21 so that there is practically no passage for air between the flange 48 and the partition 21.

Upon the flange 43 I arrange an upwardly directed collar 49 which terminates adjacent to, but is spaced outwardly from, the disc 44. The partition 21 includes air passages 50 with arms 51 therebetween.

In operation, when the motor rotor 40 is operated by leads 52 and 53 the disc 44 will be rotated, thus rotating the vanes 47 and drawing air through the ports 14 and 26 and through the apertures 50 whence the air passes through the vanes 47 and thence outwardly from the space 55 between the collar 49 and the vanes 47.

This occurs when the motor is operating and at the start of the operation of the motor the stator will turn slightly causing the parts 14 and 26 to be aligned. When the motor ceases to operate the spring 29 will cause the valve 24 to move to closed position.

The bottom closure 12 has a depending sleeve 60 thereon. This sleeve 60 has an internal flange 61 which is spot welded as at 62 to the closure 12. The sleeve 60 has an internal flange 63 thereon which supports a porcelain lamp socket supporting member 64. The supporting member 64 includes a lamp socket 65 from which a lamp 66 depends. Suitable leads 67 and 68 supply current to the lamp. The sleeve 60 is provided with a plurality of spaced screws 70 which engage a shade 71 and hold the latter about the lamp 66.

In Fig. 5 I show a modification of my invention wherein similar parts are designated by similarly primed reference numerals. In the modification the housing 11', motor stator 18', etc. are similar to those previously described. The armature shaft or rotor 40' of the motor, instead of having an impeller thereon, as shown in Fig. 1, is provided with an impeller 80 which is of the usual bladed type and includes a hub 81 held in place on the armature shaft 40' by a set screw 82.

Having thus described my invention, I claim:

1. In an air impeller, an end member having a skirt thereon, said skirt having axially extending vanes thereon, said vanes being inwardly directed and inclined, said skirt having an outwardly directed flange thereon, said flange being remote from said end member and a shell supported by said flange and spaced outwardly from the outer ends of said vanes, said flange forming an end for said shell, said shell having an outlet remote from the flange.

2. In an air impeller, a motor having an armature shaft, a rotor including an end member mounted on said armature shaft, said end member having a skirt thereon, said skirt having axially extending vanes thereon, said vanes being inwardly directed and inclined, said skirt having an outwardly directed flange thereon, said flange being remote from said end member and a shell supported by said flange and spaced outwardly from the outer ends of said vanes, said flange forming an end for said shell, said shell having an open end remote from the flange.

3. In a ventilator, a housing having an air port, a motor including a rotor and a stator, means to support said motor stator for oscillation relative to the housing, a movable closure for said port, means connecting said stator and said closure whereby operation of said motor causes said movable closure to open said port, means to limit oscillatory movement between the motor stator and the housing, means normally urging said closure to position to close said port, and an air impeller driven by said motor, said air impeller being disposed to act on air passing through said port.

4. In a ventilator, a housing having an air port, a motor mounted on said housing, said motor including a rotor and a stator, means to support said motor stator for oscillation relative to the housing, a movable closure for said port,

means connecting the motor stator and the closure whereby operation of the motor causes the movable closure to open the port, means to limit oscillation of the stator, resilient means tending to move the closure in a direction opposite to that which it is moved by the stator, and an air impeller driven by said motor, said air impeller being disposed to act on air passing through said port.

5. In a ventilator, a housing having a closure at one end thereof, said closure having spaced air ports, a motor in said housing, said motor including a rotor and a stator, means to support said motor stator for oscillation relative to the housing, a movable closure for said ports, means connecting the motor stator housing and the closure whereby operation of the motor causes said closure to move to open said ports, means tending to move the closure in a direction opposite to that which it is moved by the stator, an impeller and means whereby said motor drives said impeller, said air impeller being disposed to act on air passing through said ports.

25 6. In a ventilator, a housing having means thereon adapted to engage a ceiling, said housing having a closure at the lower end thereof, said closure having an air port, a motor in said housing, said motor including a rotor and a stator, means to support said motor stator for oscillation relative to the housing, a movable closure disposed upon said first closure, said movable closure having a port alignable with the port in said first closure, means connecting the motor stator and the closure whereby operation of the motor causes the movable closure to open the port, means to limit movement of the closure, resilient means tending to move the closure in a direction opposite to that which it is oscillated by the stator, and an air impeller driven by said motor, said air impeller being disposed to act on air passing through said port.

45 7. In a ventilator, a cylindrical housing having a flange thereon adapted to engage a ceiling, said housing having a closure at the lower end thereof, said closure having spaced air ports, said closure having a recess therein, a motor including a rotor and a stator, said stator including a hub fitting said recess for oscillation therein, a movable closure disposed upon said first closure, said movable closure having ports therein alignable with the ports in said first closure, means connecting the motor stator and the closure whereby operation of the motor causes the movable closure to open the ports, means to limit movement of the closure, resilient means tending to move the closure in a direction opposite to that which it is moved by the stator, a partition in said housing and spaced from the bottom closure thereof, said partition having apertures therethrough and having a central recess therein, said motor stator having a boss fitting said partition recess, said motor rotor having an armature shaft, the top of said recess having a hole receiving said armature shaft, and an air impeller mounted on said armature shaft above the partition, said air impeller being disposed to act on air passing through said ports.

60 8. In a ventilator, a housing having means thereon adapted to engage a ceiling, said housing having a closure at the lower end thereof, said closure having spaced air ports, a motor in said housing, said motor including a rotor and a stator, means to support said stator for oscillation, a movable closure for said ports, means

connecting the motor stator and the closure whereby the operation of the motor causes the movable closure to open the ports, means to limit movement of the closure, means to move the closure in a direction opposite to that which it is moved by the stator, a partition in said housing and spaced from the bottom closure thereof, said partition having apertures therethrough, said motor rotor having an armature shaft, a fan rotor mounted on said armature shaft above the partition, said fan rotor including an end member having a depending skirt thereon, said skirt having axially extending vanes therein, said vanes being inwardly directed and inclined, said skirt having an outwardly directed flange 15

thereon, a shell supported by said flange and spaced from the outer ends of said vanes, said shell having a closed bottom and having an open top, said rotor being disposed adjacent to 5 said partition, said rotor being adapted to act on air passing through said ports.

9. In an air impeller, an end member having a skirt thereon, said skirt having axially extending vanes thereon, said vanes being spaced apart 10 and inclined, said skirt having an outwardly directed flange thereon, a shell spaced outwardly from the outer ends of said vanes, a closure for one end of said shell, the other end of said shell having an opening forming an air outlet.
